US0D1102492S

(12) **United States Design Patent** (10) **Patent No.:** **US D1,102,492 S**
(45) **Date of Patent:** **** Nov. 18, 2025**

(54) **DRIVE PLATE**

- (71) Applicants: **DIAMOND PRODUCTIONS LTD.**,
Montreal (CA); **Eric Gallup**, Rochester
Hills, MI (US)
- (72) Inventors: **Harvey Stark**, Montreal (CA); **Eric
Gallup**, Rochester Hills, MI (US);
Pavel Ikonomov, Laval (CA)
- (73) Assignee: **DIAMOND PRODUCTIONS LTD.**,
Montreal (CA)

(**) Term: **15 Years**

(21) Appl. No.: **29/862,862**

(22) Filed: **Dec. 13, 2022**

(51) LOC (15) Cl. **15-01**
(52) U.S. Cl. **D15/5**
USPC **D15/5**
